UNITED STATES PATENT OFFICE.

ELNORA E. BALDWIN, OF RAND, COLORADO.

MARCEL HAIR WAVER.

Application filed November 17, 1926. Serial No. 148,841.

This invention relates to improvements in Marcel hair wavers and has reference more particularly to a hair waver which does not require the use of heat in producing the desired effect.

It is the object of this invention to produce a simple and effective Marcel hair waver that can be cheaply constructed and which will be very effective in its operation.

10 It is the further object of this invention to produce a hair waver of the type indicated which shall be easily applied to the hair and which will not be uncomfortable to the wearer.

15 As these hair wavers may be kept in place over night, it is quite essential that they shall be made of such material and in such a way that they will cause the least possible discomfort. For this purpose I have constructed my hair waver of rubber which is 20 flexible and yielding and will therefore produce very little discomfort. It is also quite necessary in order to produce satisfactory results, that the parts shall be so designed 25 and so related to each other that the hair, after having been waved will present a smooth and uniform wave.

The above and other objects which may become apparent as the description proceeds 30 are obtained by means of a construction which I will now describe in detail, reference for this purpose being had to the accompanying drawing in which my invention has been illustrated and in which:

35 Fig. 1 is a top plan view of my device;
Fig. 2 is a section taken on line 2—2,
Fig. 1;

Fig. 3 is a section taken on line 3—3,
Fig. 1; and

40 Fig. 4 is a view similar to that shown in Fig. 1 showing the hair in place.

My device as above indicated is made from rubber such, for example, as that employed in the construction of automobile tires, the 45 object being to produce a device that shall be flexible and at the same time have the necessary rigidity to function properly, for the purpose for which it is intended.

50 Numeral 1 designates what may be termed the body portion of the device and has a cross section substantially U-shaped. This central body section has its ends provided with rounded heads of somewhat larger cross section than the remaining portion. 55 These heads have been indicated by reference numeral 2 and serve as a means for attaching the rubber clamping bands 3 in

the manner shown in Figs. 1 and 4. Extending outwardly from opposite sides of the central portion 1, are fingers 4 whose cross sections are substantially as shown in Figure 2. These fingers are preferably staggered in the manner indicated in the drawing and there are an odd number on one side and an even number on the other; in the illustration given there are five fingers on one side and four on the other, although any other number may be used. From Figs. 2 and 3, it will be noted that the under side of the body member 1 and of the fingers 4 are 60 rounded so that the hair will be given a smooth curl. The upper surface is flat for the reason that this simplifies the construction of the mould and cheapens the process of manufacture, although I want it understood that the two sides may be exactly alike if this should be found desirable.

My improved hair waver is used in the following manner. The hair, which has been indicated by numeral 5 in Figure 4 is 65 separated into strands of the proper size. These are then wound under the fingers and over the top of the body member so as to form a series of alternate loops in the manner clearly shown in Figure 4. After the 70 hair has been wound onto the device, the rubber band 3 is put into place and this prevents the hair from becoming unwound. If the hair is short, it may require only a few 75 of the fingers to accommodate the particular lock of hair, but the operation of the device will be equally successful whether all or only a few of the fingers are employed.

It is evident from the drawing that the very tips of the hair will not be waved and 80 it is therefore necessary to use an iron for finishing the operation, but since only one application of the iron is necessary for each lock, this operation can be speedily performed.

85 It is also evident that two or more locks of hair can be wound on the same device, if desired, as the device will operate successfully until the notches between the adjacent fingers are entirely filled. It is not recommended, however, that the device be entirely 90 filled, as this will naturally cause a variation in the size of the waves.

95 From the above it will be apparent that I have produced a very simple and convenient device which can be readily applied and which will produce satisfactory results. The fact that this device is made of yielding material as above pointed out makes it 100 105 110

possible to wear it at night without experiencing any discomfort.

Having thus described my invention what I claim as new is:

1. A device of the class described consisting of an elongated body member composed of soft, resilient material and having fingers extending from opposite sides thereof, the fingers on each side being spaced from one another, the body member extending beyond the fingers and being reduced in size adjacent its ends to facilitate the attachment of a retaining device.

2. A Marcel hair waver consisting of a body member having a plurality of spaced fingers formed integral therewith and ex-

tending outwardly from opposite sides thereof, the device being composed of soft resilient material and made flat on one side.

3. A device of the class described comprising an elongated body member composed of soft resilient material and having fingers formed integral therewith, extending from opposite sides thereof and spaced from one another, the body member extending beyond the fingers at both ends, and an elastic band adapted to be connected with the extensions of the body member for holding the hair in place.

In testimony whereof I affix my signature.

ELNORA E. BALDWIN.
